UNITED STATES PATENT OFFICE.

LAURA V. ROBINSON, OF BALTIMORE, MARYLAND.

SCRAPING DEVICE.

1,224,793.

Specification of Letters Patent.

Patented May 1, 1917.

Application filed June 15, 1914. Serial No. 845,230.

To all whom it may concern:

Be it known that I, LAURA V. ROBINSON, a citizen of the United States, residing at Baltimore, in the State of Maryland, have 5 invented certain new and useful Improvements in Scraping Devices, of which the following is a specification.

My invention relates to new and useful improvements in cleaning brushes and the 10 like and has for its primary object to provide a simple and effective scraping brush that is particularly designed for cleaning soiled kitchen utensils and the like and consists of a handle carrying a detachable head 15 in which is mounted a plurality of scraping blades that are closely arranged relative to one another in such manner that a reliable scraping action is provided.

Another object is to provide a scraper of 20 the character described that is formed with a novel arrangement of scraping blades whereby pots, pans and other articles may be scraped in a reliable and expeditious manner and with considerable force without 25 loosening or breaking the scraping blades.

Another object is to provide a device of 30 the character described that is of an extremely simple construction, is reliable and efficient in operation and inexpensive to 35 manufacture.

The above and additional objects are accomplished by such means as are illustrated in the accompanying drawings, described in the following specification and then more 40 particularly pointed out as claimed.

With reference to the drawings, wherein I have illustrated the preferred embodiment 45 of my invention as it is reduced to practice, and throughout the several views of which 50 similar reference numerals designate corresponding parts.

Figure 1 is a bottom plan view of my improved scraping brush, and

Fig. 2 is a vertical sectional view thereof. 45 Referring to the drawings by characters of reference, the numeral 1 designates a handle or body portion of my improved brush that is preferably provided with rounded edges and formed at one end with an enlarged slightly offset and circular head portion 2. Secured to the head 2 and on one face thereof is a circular disk or body 3 that is provided with a beveled or inclined side wall 4 and is secured by means of screws 5 that are inserted through the head portion and into the disk or body 3. The inclined or

beveled peripheries 4 of the disk or body 3 provide a body that has a small outer face and an enlarged inner face. Inserted in openings in the side and outer faces of the 60 disk or body 3 is a plurality of scraping blades 6. The blades 6 on the outer face of the disk 3 are arranged in radially extending spaced rows, and the blades forming each row are arranged in spaced relation, as 65 shown in Fig. 1 of the drawing. The circular row of blades that is located at the point of juncture between the outer face of the disk and the beveled periphery of the disk, extend outwardly at obtuse angles to 70 the outer face of the disk, and the blades that are mounted on the beveled periphery of the disk are arranged in superposed circular rows, and extend horizontally and in planes located above the spaces between the 75 radial rows of teeth on the outer face of the disk. Each blade 6 is tapered inwardly toward its secured end and is formed of a preferably flat and thin steel strip. The blades 6 project outwardly from the body 3 80 on all of the free sides and faces thereof in such manner that an effective scraping surface is provided and the cleaning of pots, pans and other articles or utensils may be readily effected. The blades 6 project outwardly for a distance equivalent to approximately half their length and it will be readily seen that derangement thereof is prevented, to an appreciable extent.

The body 3 is approximately the same size 90 as the head 2 so that the brush may be used to cleanse or scrape the corners of receptacles and the like without interference by the handle or head. The circular head 2 projects slightly beyond one horizontal side 95 of the handle and has removably secured thereto the blade carrying disk 3, which blades due to their peculiar formation thereon permits the crevices and curves of pots, pans, or other cooking utensils to be 100 thoroughly cleaned.

In practice, I have found that the form of my invention, illustrated in the drawings and referred to in the above description, as the preferred embodiment, is the most efficient and practical; yet realizing that the conditions concurrent with the adoption of my device, will necessarily vary, I desire to emphasize the fact that various minor changes in details of construction, proportion and arrangement of parts may be resorted to, when required, without sacrificing 110

any of the advantages of my invention, as set forth.

What is claimed is:—

A scraping device comprising a handle, a circular enlargement at one end of the handle, said enlargement projecting slightly beyond one horizontal side face of the handle, a disk removably secured to the projecting face of said circular enlargement, said disk 10 having its periphery beveled, a plurality of scraping blades secured to the outer face of the disk at a spaced distance apart and, arranged in radial spaced rows, a circular row of spaced blades arranged on the beveled pe-

riphery of said disk and extending outwardly therefrom at an obtuse angle and a second circular row of spaced blades secured to and extending outwardly from the beveled portion of the disk and located in a plane below the first named circular row, as 15 20 and for the purpose specified.

In testimony whereof I affix my signature in presence of two witnesses.

LAURA V. ROBINSON.
